UNITED STATES PATENT OFFICE.

WILHELM BITTROLF, OF PFORZHEIM, GERMANY, ASSIGNOR TO ERNST GIDEON BEK, OF PFORZHEIM, GERMANY.

SOLDERING MACHINE.

Application filed January 31, 1923. Serial No. 616,201.

To all whom it may concern:

Be it known that I, WILHELM BITTROLF, a citizen of the German Empire, and a resident of Pforzheim, Germany, have invented 5 new and useful Improvements in Soldering Machines, of which the following is a specification.

This invention relates to the soldering of chain mail or wire mesh by passing it continuously between two rows of flames with the least possible expense of heat, without 10 damaging the chain mail and soldering one piece of chain mail by one procedure from end to end.

15 With this object in view the chain mail is mounted at its upper edge hanging vertically from a vertically moving carrier, so that it is adapted to traverse the flames in vertically hanging position.

20 The regular downward movement is preferably produced by suspending the upper edge of the chain mail on a horizontal carrier which itself is suspended at its two ends by two chains adapted to execute a 25 feed motion in downward direction.

The chain mail is guided in proximity of the flames in order to smooth the small folds formed owing to the chain mail hanging down, as said folds would prevent that all 30 parts of the chain mail traverse exactly the right zone of highest temperature of the flame. For this purpose two cylinders are provided arranged at different heights above the flames and near the same, said 35 cylinders bearing from both sides against the chain mail with slight pressure but not pressing it between their surfaces, so that they can be made from metal resisting the heat near the flames without damaging the 40 chain mail.

The slight pressure is preferably produced by using small counterweights arranged upon the arms which support the cylinders, to press said cylinders against the 45 freely suspended chain mail without any counter-pressure of another cylinder.

Two similar guide cylinders are preferably mounted below the rows of flames as near to them as possible, where the chain 50 mail proceeds upon a conveying band which carries it off in horizontal direction. Two holders are preferably arranged for the chain mail so that, if the chain mail changes its direction of movement when getting 55 upon the conveying band one holder which

has passed also through the flames and the guiding cylinders, drops automatically off the chains before they resume the movement in vertical direction, so that upon this holder can be refixed whilst the second holder with the chain mail is passing with its chain mail between the flames.

60 In the drawing, Fig. 1 shows the machine in front elevation partly in section. Fig. 2 is a side elevation of the machine partly in section, several parts being omitted.

The uprights *a*, *a* fixed in a base plate *a'* are connected at the top by a cross bar *a''*. In the uprights *a*, *a* sprocket wheels *b*, *b* are arranged at the upper ends over which the chains *c*, *c* are guided which are further guided over the sprocket wheels *b'*, *b''* arranged upon the base plate. The sprocket wheels *b''* are keyed upon a common shaft *b'''* which is revolved mechanically and may be 70 revolved by hand. On the chains *c*, *c* the holder bars *d*, *d* are fixed which have hooks *d'*, *d''* on which the holders *f*, *f* for the chain mail are suspended designed to carry by means of hooks or pins *f'* the chain mail *g*. The well known burner tubes *m*, *m* are fed with combustible mixture through their hollow axles. Each burner tube *m* is mounted upon rollers *m'*, *m''* and a horizontal reciprocating motion with regard to the chain mail *g* is communicated to said burner tubes from a cam cylinder *m'* the curved groove of which acts upon the lower 80 end of a stud *m''* fixed by a collar *m'''* upon the hollow axle of the corresponding burner.

85 *h* and *h'* are the two upper smoothing cylinders which are mounted in the movable arms *k*, *k'* having counterweights *l*, *l'*. The cylinders *h*, *h'* are arranged the one 90 above the other at such a distance apart that they allow of the passage of the carrier *d* and the holder *f* and do not clamp the wire chain between their surfaces but press merely, without any counter pressure, 100 against the hanging chain mail. Below the burner tubes the two guide cylinders *q*, *q'* are mounted in arms *q''*, *q'''* and *q''', q''''* so that they bring the chain mail somewhat out of its initial direction in order to assist in preventing the soldering together of several adjacent meshes. *n* is a conveyor band guided by cylinders *n'*, *n''* and designed to deliver 105 the cooled chain mail into the gutter *p*.

110 The hand drive of the machine is used if

small pieces of chain mail are to be soldered and if the holder has to be rapidly lowered from its highest position. The hooks or pins d' are shaped to drop the holder f when assuming horizontal position on the conveyor band n . So each holder may be remounted with a suspended piece of mail during the ascent of the holder bar d .

- 10 The mail chain carrier may be constructed to carry a roll of chain mail, if one piece of chain mail is longer than the height of the machine.

Instead of endless chains any other conveying device can be used for the chain mail, for instance screw spindles designed to lower and raise the chain mail holder. For the conveying band a simple inclined piece of sheet iron may be substituted which might be agitated by a shaking motion.

Now what I claim and desire to secure by Letters Patent is the following:

1. In a soldering machine of the described class the combination of a vertically guided chain mail carrier, adapted to carry chain mail to burners to solder the same, means to suspend chain mail vertically hanging on said carrier, burners placed at both sides of the chain mail, means to move downward the said carrier and means to convey the mail sideward below the burners.

2. In a machine as described in claim 1 a smoothing cylinder above the burners touching with slight pressure the suspended chain mail.

3. In a soldering machine of the described class, the combination of a vertically guided chain mail carrier adapted to carry chain mail to burners to solder the same, means to suspend chain mail vertically hanging on said carrier, burners placed at both sides of the chain mail, smoothing cylinders arranged one above the other at opposite sides of the chain mail, means to move downward the said carrier and means to convey the mail sideward below the burners.

4. In a machine as described in claim 1 a smoothing cylinder mounted below the burners.

5. In a machine as described in claim 1 two smoothing cylinders mounted below the

burners at different heights one above the other.

6. In a machine of the described class an endless carrier to suspend chain mail vertically thereon and to convey said chain mail to burners to solder the same, two series of burners, and means to move the mail and the carrier through the flames between the burners.

7. In a machine of the described class in claim 6, two carriers fixed at different points to the moving elements.

8. In a machine as described in claim 1 a carrier consisting of an holder bar fixed to the moving means, a holder detachably fixed to the holder bar and provided with pins to insert into the upper edge of the chain mail.

9. In a soldering machine of the described class, the combination of a vertically guided chain mail carrier adapted to carry chain mail to burners to solder the same, a holder bar fixed to the carrier, a holder detachably fixed to the holder bar, means to change the direction of the mail below the burners from the vertical direction and pins at the holder appropriately shaped to drop the holder at said change of direction.

10. In a machine of the class described endless chains having a vertical downward motion, chain mail carriers fixed to said chains, rollers to direct the chains sideward at the lower side of the machine, burners arranged above the plane of the said change of direction of the chains, a smoothing cylinder arranged above the burners, means to receive the chain mail below said plane and to direct it sideward from its vertical suspension plane.

11. In a machine for soldering chain mail, an endless conveyor adapted to carry chain mail to heating means to solder the same, a heating means adapted to direct heat through a given path, means for feeding the conveying means through said heating path whereby the chain mail is heated to reduce the solder and means for spacing the conveyor from the heating means.

In testimony that I claim the foregoing as my invention I have signed my name.

WILHELM BITTROLF.
